METHOD OF ELIMINATING CROSS TALK IN PHANTOMED TRANSMISSION SYSTEMS.

Application filed July 15, 1926, Serial No. 122,742, and in Germany July 18, 1925.

This invention relates to phantomed transmission systems and particularly to methods for reducing cross-talk within and between adjacent phantomed lines.

5 Cross-talk in multiple telephone cables occurs principally between specially connected speaking circuits. These are the speaking circuits belonging to a quad, i. e., the phantom circuit and the two side circuits and 10 also the speaking circuits of two quads placed near to each other in the cross-section of the cable. Methods for balancing out the cross-talk between the speaking circuits of a quadded cable and also between the phantom circuits of two quads are well known. 15 On the other hand no method has been known heretofore, for balancing the cross-talk between all the speaking circuits of two cable quads. Experience has proved it to 20 be a necessity, however, to extend the balancing of the cross-talk to all the speaking circuits of two mutually related cable quads. This invention relates to the solution of this problem.

25 The invention is based upon the well known fact that cross-talk between two cable lines is mainly due to the presence of capacity couplings, the elimination of which, by inserting suitably proportioned condensers between particular wires of the inducing lines, is theoretically possible. Between the 30 three speaking circuits of each of two cable quads there are nine couplings, viz., one coupling between the two phantom circuits, four couplings between the phantom and side circuits, and four couplings between the side circuits. These three kinds of couplings, 35 phantom to phantom, phantom to side, and side to side, are dependent on each other so that generally in varying a coupling, for example by balancing the same by means of additional condensers, each coupling of the other kinds is also varied in its original magnitude. Similarly, the cross-talk couplings 40 within a single phantomed circuit or quad are dependent upon the couplings of the circuits of that quad with the circuits of neighbouring quads. A direct capacity balance is thus not possible.

45 Broadly this invention consists in balancing the individual speaking circuits in such manner that the balancing arrangements act as far as possible independently of each

other, or so that they influence each other in such a manner as to simplify the process. 55

According to a feature of this invention the couplings between the speaking circuits of neighbouring quads are first balanced and then the couplings within each quad are balanced. As the balancing of the cross-talk 60 coupling effects within a phantomed circuit affects the balance of the cross-talk between the speaking circuits of the adjacent phantomed circuits, those changes in the couplings within the phantomed circuit, which 65 have been caused by the previous balancing of the couplings between the circuits of the adjacent phantomed circuits, can be taken into account at the time the couplings within a circuit are balanced. If, on the other 70 hand, the succession were reversed, the balancing within the quad would be again disturbed by balancing the cross-talk between the circuits of adjoining quads.

According to another feature of this invention, a certain order of procedure is adhered to in balancing the couplings between the circuits of the adjacent quads, namely the couplings between the phantom circuits are balanced after the side to side and phantom to side couplings have been balanced. 75 If, when balancing the phantom to phantom couplings quadruple condensers, such as are described in German Patent No. 396,634, are used, the phantom to phantom balance 80 may be made without any influence on the phantom to side and side to side balance.

Moreover, it is necessary to balance the phantom to side couplings and the side to side couplings independently of each other. 90 This can be done in the following manner:

As is well known, the couplings are composed of the sums and differences of the component capacities between the individual wires, so that mutually dependent couplings 95 contain the same component capacities in common. Thus each phantom to side coupling contains the sum or the difference of two component capacities which conversely appear as a difference or a sum in one and only one side to side coupling. Therefore, if, when balancing, for example a phantom to side coupling, the inserted capacity value is divided into two equal parts 100 each of which is placed in parallel with one of the two component capacities, thus

adding together in their effect on the couplings being balanced, then all side to side couplings, even those containing these component capacities, maintain their original magnitudes. This is due to the fact that the variation of one component capacity is neutralized by a variation of similar magnitude of the other component capacity which is connected, in this case, in an opposite manner. The balance of phantom to side and side to side couplings must thus be made in such a manner that each coupling is balanced by two equal condensers which are connected to the wires of the cable in such a way that the component capacities, which add together in pairs in their effect on the coupling, are in parallel.

In balancing the phantom to side couplings there are two ways of inserting the condensers, one having a positive and the other a negative effect on the phantom to phantom coupling. It is advantageous to so insert the condensers that simultaneously with the balancing of the phantom to side coupling the amount of the phantom to phantom coupling is reduced. Thus, the use of a special condenser for phantom to phantom balancing may be avoided, if, by doing this, the phantom to phantom coupling is reduced to the tolerance value or at least the value of the condenser required for the phantom to phantom balance is reduced. The practical accomplishing of cross-talk balancing between the speaking circuits of different phantommed circuits can be done as follows:—

The two cable quads are connected through a rheostat to a coupling meter by means of special leads. By varying the switch positions the cable wires can be connected in nine combinations to the coupling meter and in the various switch positions the following couplings can be measured:—

Phantom I to phantom II, side 1 of the quad I to phantom II, side 2 of the quad I to phantom II, phantom I to side 1 of the quad II, phantom I to side 2 of the quad II, side 1 of the quad I to side 1 of the quad II, side 2 of the quad I to side 1 of the quad II, side 1 of the quad I to side 2 of the quad II, side 2 of the quad I to side 2 of the quad II.

The method of the invention for reducing cross-talk couplings within and between adjacent phantommed lines will be clear by inspection of the accompanying drawing, Fig. 1 of which shows schematically the cross-talk couplings existing between the various speaking circuits of two phantommed quads in a multiple telephone cable and Fig. 2 of which is a table indicating the preferable order of procedure in accordance with the invention for balancing out these cross-talk couplings.

Referring to Fig. 1 of the drawing, two adjacent quads Q_1 and Q_2 are shown, the

quad Q_1 comprising side circuits S_1 and S_2 and phantom circuit P_1 , and the quad Q_2 comprising side circuits S_3 and S_4 and phantom circuit P_2 . The cross-talk couplings between the circuits of the adjacent quads and between the circuits within the quads are indicated by the arrows extending between the various circuits. As indicated in the table of Fig. 2, the order of balancing the cross-talk couplings is first, to balance the coupling between the speaking circuits of the adjacent quads, i. e. the side to side and side to phantom couplings in any desired order, secondly, to balance the coupling between the phantom circuits of the adjacent quads, and thirdly, to balance the couplings within each quad in any desired order.

The determination of the cable wires to which the various balancing condensers are to be connected can be facilitated by using a tabulated record. The number of the couplings to be balanced would of course be large if it were not limited for practical reasons to only the couplings between the speaking circuits of those quads which need to be balanced because they lie close together and parallel to each other in the cross-section of the cable, and further by the fact that a certain tolerance in the accuracy of balancing is allowable.

What is claimed is:

1. The method of eliminating cross-talk between the speaking circuits of different phantommed lines or quads by means of condensers, characterized in this that first the cross-talk couplings between the circuits of adjacent quads are balanced and then the cross-talk couplings within each quad are balanced.

2. A method in accordance with claim 1, characterized in this that in balancing the cross-talk between circuits of the different quads the side to side and phantom to side couplings are first balanced and then the phantom to phantom couplings are balanced.

3. A method in accordance with claim 1 characterized in this that each coupling for the phantom to side and side to side cross-talk is balanced by two condensers of half the coupling capacity, said condensers being connected in parallel to the two component capacities so as to add together in their effect on the coupling which has to be balanced.

4. A method in accordance with claim 1 characterized in this that such partial capacities are used for balancing the phantom to side couplings that at the same time the phantom to phantom coupling is reduced.

In witness whereof, we hereunto subscribe our names this 2nd day of July, A. D. 1926.

HANS KARSTEN.

KARL KÜPFMÜLLER.
